UNITED STATES PATENT OFFICE.

GEORGE H. DUNBAR, OF NEW ORLEANS, LOUISIANA.

CAN-CLOSURE.

No. 844,108.

Specification of Letters Patent.

Patented Feb. 12, 1907.

Application filed March 6, 1906. Serial No. 304,567.

To all whom it may concern:

Be it known that I, GEORGE H. DUNBAR, a citizen of the United States, residing at New Orleans, in the parish of Orleans and State of Louisiana, have invented new and useful Improvements in Can-Closures, of which the following is a specification.

This invention relates to cans, and particularly to means for closing the latter, and has for its object to provide a novel and simple top for a can provided with an imperforate removably-depressed element which is integrally formed with the can-top and at the time that the latter is shaped and constructed and which must be removed by cutting when it is desired to gain access to the contents of the can and has an auxiliary cover to coöperate therewith to preserve and avoid deterioration by a continuous exposure to the air of the contents of the can after the top is opened.

To the ends stated the invention consists in the construction and arrangement of parts, which will be more fully hereinafter set forth.

In the drawings, Figure 1 is a sectional elevation of the head portion of a can, showing the improved top applied thereto and the auxiliary cover arranged above the same. Fig. 2 is a similar view showing the imperforate depressed part having the opening formed therein by cutting the same and the auxiliary cover applied thereto. Fig. 3 is a view similar to Fig. 2, showing the auxiliary cover in position for removal from the depressed part of the top. Fig. 4 is a top plan view of the can as it appears before the depressed part thereof is cut and without the auxiliary cover. Fig. 5 is a view similar to Fig. 4, showing the auxiliary cover applied.

Similar numerals of reference are employed to indicate corresponding parts in the several views.

The numeral 1 designates the can-body, which is of ordinary or usual construction and provided with a top 2, the upper edge of the body being primarily constructed with an outwardly-projecting surrounding flange 3 and the top having a corresponding flange 4, the flanges 3 and 4 being secured by crimping or seaming the same to the body of

the can without the use of solder or acid. The top 2 is formed with a depression or dish-shaped cavity 5, which is stamped therein at the time that the said top is struck or cut out of tin-plate. The dish-shaped cavity is thus constructed integral with the top, and the bottom thereof is imperforate, and when it is desired it will also have impressed therein by suitable dies the words "Cut this out." After the top is applied to the can and secured the contents of the can are only accessible by removing the bottom of the depression or dish-shaped cavity 5. When the bottom of the depression or dish-shaped cavity 5 is removed by cutting out the same, the contents of the can may be preserved against deteriorating influences of the surrounding atmosphere through the medium of a dish-shaped auxiliary cover 6, which is frictionally held in the depression and has a flange 7 surrounding the same. The flange 7 projects over the portion of the top adjacent to the depression or dish-shaped cavity 5 and is removable by introducing a suitable implement between the flange 7 and the can-top and exerting a prying operation on the said implement. The bottom of the auxiliary cover 6 will also have impressed or stamped therein the words "Pry this up."

From the foregoing it will be observed that the can constructed in accordance with the features of this invention is made without any opening or filling mouth, the can-body having its contents placed therein prior to the application of the top, and after the said top is secured, as hereinbefore set forth, the can will be hermetically sealed without the use of solder or acid, and by this means a sanitary can will be provided.

It will also be understood that the can may be made in various dimensions and that the position of the depression or dish-shaped cavity 5 may be modified without departing from the features of the invention.

Having thus described the invention, what is claimed is—

1. The combination with a can-body, of a one-piece top connected to the upper edge of the can by a hermetic joint, said top having an integral depression with an imperforate

bottom adapted to be cut out, and a removable cap for such depression, said cap having a downwardly - extending wall which fits snugly in the side walls of said depression in the top.

5 2. The combination with a can-body, of a one-piece top seamed to the upper edge of the body and having an integral depression with an imperforate bottom adapted to be

cut out, and a removable cap frictionally fitted within the depression.

In testimony whereof I have hereunto set my hand in presence of two subscribing witnesses.

GEORGE H. DUNBAR.
